UNITED STATES PATENT OFFICE.

ALBERT W. HENNING, OF NEWARK, NEW JERSEY.

JEWELRY.

1,069,254.

Specification of Letters Patent.

Patented Aug. 5, 1913.

Application filed April 8, 1912. Serial No. 689,124.

To all whom it may concern:

Be it known that I, ALBERT W. HENNING, a citizen of the United States, residing at Newark, in the county of Essex and State 5 of New Jersey, have invented certain new and useful Improvements in Jewelry; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 The invention herein set forth has reference to a novel finger-ring, cuff-button, or similar article of jewelry which is provided with an interchangeable or removable plate adapted to carry a monogram, emblem, 20 jewel, or other decorative feature.

The invention has for its principal object 25 to provide a novel removable or interchangeable plate for finger rings and similar articles of jewelry, with a novel construction of means for locking the said plate to the article of jewelry to which it is applied, in a secure manner, so that accidental displacement or removal of the same 30 is eliminated.

Other objects of the present invention 35 not at this time more particularly enumerated, will be clearly evident from the following detailed description of the said invention.

With the various objects of the present 40 invention in view, the said invention consists, primarily, in the novel removable or interchangeable plate for articles of jewelry and the locking means therefor hereinafter 45 set forth; and, the invention consists, furthermore, in the novel arrangements and combinations of the several devices and parts, as well as in the details of the construction of the same, all of which will be 50 more fully described in the following specification, and then finally embodied in the clauses of the claim which are appended to and which form an essential part of the 55 said specification.

The invention is clearly illustrated in the 50 accompanying drawings, in which:—

Figure 1 is a top view of a finger ring provided with the novel construction of interchangeable or removable plate secured thereto; Fig. 2 is a side elevation of the 55 same; and Fig. 3 is a transverse vertical section of the same, said section being taken on line 3—3 in said Fig. 2, looking upwardly. Fig. 4 is a detail vertical cross-section, taken on line 4—4 in said Fig. 1, 60 said view being drawn upon an enlarged scale; Fig. 5 is a view similar to Fig. 4, but illustrating the locking means in its unlocked position and the interchangeable or removable plate removed from the ring; 65 and Fig. 6 is a horizontal section, taken on line 6—6 in said Fig. 4, looking in the direction of the arrow α . Fig. 7 is a plan view of the inner side of the removable or interchangeable plate; and Fig. 8 is a cross-section 70 of the same, said section being taken on line 8—8 in said Fig. 7. Fig. 9 is a vertical cross-section, similar to Fig. 4, but illustrating the removable or interchangeable plate provided with a jewel-setting and 75 a jewel.

Similar characters of reference are employed in all of the herein-above described views, to indicate corresponding parts.

Referring now to the said drawings, the 80 reference-character 1 indicates the ring-body, or the body of any other article of jewelry, to which it is desired to apply the present invention. The upper portion of said ring-body 1 is provided with a part 2 85 formed with a suitable opening 3 for the reception of a depending flange or skirt-portion of a removable and interchangeable plate, to be hereinafter more fully described. The arch 4 of said ring-body 1, which forms 90 with the portion 2 a chamber, is provided with a countersunk portion 5, said portion 5 being formed with an opening 6 which provides a bearing for a pivot-stud 7, the head 8 of which resides in said counter- 95 sunk portion 5, in such a manner so as to expose the said head 8 on the inner side of said arch 4 of the ring-body 1. The said

- exposed surface of said head 8 is provided with recesses 9, or a slot, for the reception of a suitable tool, such as a spanner-key or screw-driver, whereby said pivot-stud 7 may be turned in its bearing. Said pivot-stud 7 is further provided, at its inner or upper end with a reduced extension or rivet-portion 10, and secured upon the said pivot-stud, by means of said reduced extension or rivet-portion 10, is a latch-member or turn-button 11, which is provided with oppositely extending arms 12, which form the movable members of the locking means for securing said plate in its assembled relation upon said ring-body, the said arms 12 possessing preferably a certain amount of resiliency or "spring" with relation to the main body of said latch-member or turn-button 11.
- 20 The reference-character 13 indicates the novel construction of the interchangeable or removable plate, the face or exposed surface of which may be provided with an engraving, etching, or other form of embellishment or ornamentation; or, it may be provided with a setting 14 for securing thereon one or more jewels 15 or other ornamental elements. The said plate 13 is provided upon its under side with a downwardly extending annular flange or skirt 16, the same being offset from the marginal edges of said plate, so as to provide, at said marginal edges, a rim-portion 17 being adapted to engage with and to be seated upon the hereinabove mentioned seat formed by the upper marginal surface of the portion 2 of the ring-body. Said flange or skirt 16 is adapted to be received and telescope into said opening 3 of the said chambered portion 2 of the ring-body, and suitably connected with said flange or skirt 16, and extending inwardly is a rim or ledge-portion 18, said rim or ledge-portion 18 being provided with a pair of latch-lugs 19, which are positioned opposite or across from each other. Each latch-lug 19 is provided, at each lateral end or side thereof, with notched or cutaway portions 20, which form at each side of said latch-lugs 19 outwardly projecting guide-fingers 21, said guide-fingers being inclined downwardly so as to provide an inclined guiding surface for both lifting and guiding the resilient arms 12 of said latch-member or turn-button 11 into their holding engagement with the upper surface of said latch-lugs 19, when the said latch-member or turn-button 11 is turned, thereby locking the said plate 3 in its assembled relation with said ring-body 1.
- 60 The advantage of the hereinabove described arrangement is that when the latch-member or turn-button 11 is turned into engagement with said latch-lugs 19, the arms 12 of the former being slightly lifted

at their engaging ends, tend to create a 65 spring-like tension due to the resilience of said arms 12 so as to draw the said plate 3 down and seat the rim-portion 17 of the same firmly upon the seat of the chambered portion 2 of the ring-body 1, and also at 70 the same time firmly retain the plate 3 in its attached relation to said ring-body, as will be clearly evident from an inspection of the several figures of the drawings.

I do not limit the shape or design of the 75 plate, or its peripheral configuration, to any particular shape or outline, as it is evident that in such respect the same may be subject to a wide variation.

I am also aware that changes may be 80 made in the general arrangements and combinations of the various devices and parts, as well as in the details of the construction of the same, without departing from the scope of my present invention, as described 85 in the accompanying specification, and as defined in the clauses of the claim appended thereto. Hence, I do not limit my present invention to the exact arrangements and combinations of the devices and parts as set 90 forth in the foregoing specification, nor do I confine myself to the exact details of the construction of the said parts, as illustrated in the accompanying drawings.

I claim:—

1. In a device of the class described, a chambered body-portion provided with an opening, a seat surrounding said opening, a plate provided with a rim-portion adapted to be seated upon said seat, an annular skirt 100 connected with said plate and receivable in said opening of said body-portion, inwardly projecting latch-lugs connected with said skirt, oppositely directed downwardly inclined guide-fingers connected with the sides 105 of each of said latch-lugs, a perforated depressed portion connected with the lower portion of said chambered body-portion, a pivot-stud journaled in said perforation, an exposed head connected with said pivot- 110 stud located in said depressed portion, and a latch-member provided with oppositely extending resilient arms connected with the inner end of said pivot-stud, said head being provided with means for rotating said 115 pivot-stud and latch-member so as to engage said resilient arms with said guide-fingers and said latch-lugs.

2. In a device of the class described, a chambered body-portion provided with an 120 opening, a seat surrounding said opening, a plate provided with a rim-portion adapted to be seated upon said seat, an annular skirt connected with said plate and receivable in said opening of said body-portion, inwardly 125 projecting latch-lugs connected with said skirt, oppositely directed downwardly inclined guide-fingers connected with the sides

of said latch-lugs, a rotatable latch-member journaled in the lower portion of said chambered body-portion, said latch-member being provided with oppositely extending resilient arms, and means for rotating said latch-member so as to engage said resilient arms with said guide fingers and said latch-lugs.

In testimony, that I claim the invention set forth above I have hereunto set my hand ¹⁰ this 6th day of April, 1912.

ALBERT W. HENNING.
